UNITED STATES PATENT OFFICE.

EMMETT G. McMENAMIN, OF MONTEREY, CALIFORNIA.

AERONAUTIC TOY MOUNTING.

Application filed December 15, 1926. Serial No. 155,005.

The present invention relates to aeronautic toys for the amusement of children; although by making the device of appropriate design, size and durability it may well be used for 5 display purposes by carrying advertising matter or other indicating indicia.

For the purpose of this specification my device is illustrated as a mounting for a toy aeroplane, but obviously it could be used 10 in conjunction with toys of many different kinds.

Broadly, the device comprises a frame fashioned to represent an aeroplane, a flying bird, or some other object suggestive of 15 aerial locomotion. The said frame, above its center of gravity, being suspended turn-ably from a member adapted to run to and fro on a pair of normally horizontal and parallel cables.

20 An object of my invention therefore, is to provide a dual and flexible support for a device of this kind, said support provided at its farther end with means for attachment to any suitable stationary object at a higher 25 level from the ground than the hands of an operator of the device.

A further object is to provide for free movement of the cables in all directions at their operating ends.

30 A still further object is to provide a means for imparting at will, positive propulsive impulses to the toy.

Another object is to provide a swivel member adapted to impart stunt movements to 35 the toy.

Another object is to provide for the return of the toy with ability to arrest its progress at any point without having to elevate the cables at the operating end.

40 Other objects and advantages will appear during the course of the following description and be particularly pointed out in the claims.

I attain these objects by the herein de-45 scribed method of applying the force that is required to actuate the toy, and by the mechanism illustrated in the accompanying drawing, in which—

Figure 1 shows a plan of the device.

50 Figure 2 shows a side elevational view.

Figure 3 shows a sectional view taken on the line II—II of Fig. 1.

Figure 4 shows the swivel member for at-

taching the far ends of the cables to sta-55 tionary supports.

Similar numerals refer to similar parts throughout the several views.

In the drawing, Figure 1 shows the toy supported on the dual cables 3 and 3^a in which position the free operating ends of the cables 60 are grasped in the hands 8—8; whereas, the far ends of cables are secured to the spacing, swivel member 6—6 attached to the supporting hook 6^a that is hooked over the mold 7 of the wall 9 of a supposed room 9—10. 65

The swivel-pin 6^b which engages the mem-65 ber 6—6 with the hook 6^a has its longitudi-70 nal axis approximately parallel with that of the cables 3 and 3^a when they are tensed, so that the contacting surfaces of the member 6—6 and the hook 6^a lie in a plane perpen-75 dicular to the axes of the said cables; it fol-lows therefore, that while they are tensed, any rotation of the free ends of the cables 3 and 3^a in a plane perpendicular to the lon-80 gitudinal axis of the pin 6^b would cause the member 6—6 to turn upon its axis thus bringing the cables into varying positions with respect to each other by lowering one and elevating the other, for purposes that 85 will later appear.

The cables 3 and 3^a are bridged with the 85 traveling element 13 adapted to traverse to and fro longitudinally of the dual support-ing cables. Horizontally mounted in the ele-90 ment 13 and carried thereby are the two sheaves 12 and 12^a which are preferably so spaced apart as to dispose that portion of the said cables which extends from the sheaves to the member 6—6, so that it will 95 be parallel. The sheaves 12 and 12^a are revolvably mounted on the vertical axes 19—19, as best shown in Fig. 3.

The cables 3 and 3^a may be either two in-95 dividual cables or they may be comprised in a single cable having the two parts, 3 and 3^a.

The element 13 constitutes the traversing support for the toy which is turnably sus-pended therefrom by the vertical axis 14 that 100 engages flange 15 rigidly secured by such means as the screws 18 to the upper surface of the plane 16. Axis 14 is preferably lo-cated at the center of gravity of the toy so that it will hang true, while at the same time permitting the suspended toy to turn round in a horizontal plane.

In general appearance the toy is fastened to represent an air-ship, having a body 1, which may be of wood or the like, or be made of hollow stampel metal. The dummy propeller 2 is mounted in front and runs by air-pressure when the ship sails, a vertical rudder 4 and the horizontal planes 4^a are also provided. Further to simulate the appearance of a sure-enough air-ship the plane 16 is supported from the body 1 by the struts 11 and 11^a, shown in Fig. 2. The ship is now ready to sail and it works like this:

A would-be aviator, after first seeing the cables 3 and 3^a all clear with no snarls in them, slips the hook 6^a over some distant high point and then grasps the free ends of the two cables as shown in Fig. 1, and pulls them taut. The ship now rides suspended from the cables. As long as the hands are kept fairly close together the ship will remain at rest close to the hands but on the slightest outward movement of the hands the ship runs up the cables. The ship returns to the player head-on as the influence of the air acts upon the rudder 4 so as to cause the ship to make a half turn on the way back, but it will not return at all until the hands are brought together. Quite an interesting variety of movements can be obtained by skillful manipulation of the cables in a plane perpendicular to their

axes, such as causing the ship to run on its side or in a spiral, and many graceful darting motions can be attained, although the 35 merest child can do it.

Having thus described my invention what I claim is,—

1. A device of the kind described comprising two supporting cords disposed in the same horizontal plane, the far ends of the cords attachable to supporting objects, the near ends of the cords being free, a horizontal bridge element traversable on said cords, said element having guide openings 45 through which the cords extend and guide rollers in the openings engaging the cords, and a body suspended from the said element and swively connected thereto.

2. A device of the kind described comprising two supporting cords being disposed in the same horizontal plane, the far ends of the said cords swivelably attachable to supporting objects, the near ends of the cords being free, a bridge element traversable on said cords, spacing members carried by the element, said members constituting a means for driving the element forward when the free ends of the cords are jerked outwardly 60 under strain, and a body depending from said element, and swiveled thereon.

In witness whereof, I have hereunto set my hand this 11th day of December, 1926.

EMMETT G. McMENAMIN.
